UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

MOTOR-STARTING APPARATUS.

Application filed November 6, 1923. Serial No. 673,199.

To all whom it may concern:

Be it known that I, CHESTER D. AINSWORTH, a citizen of the United States, residing at Wollaston, in the county of Norfolk and State of Massachusetts, have invented an Improvement in Motor-Starting Apparatus, of which the following is a specification.

This invention relates to apparatus and systems for starting electric motors.

A relatively large electric motor may take many times its normal full load running current when it is first brought up to normal running speed and if connected directly to the line for starting, may cause considerable disturbance to the line. For this reason appropriate motor starting apparatus is or may be provided which is adapted to reduce line disturbance during the starting of the motor.

The motor starting apparatus usually includes a starting switch and an independent running switch. The starting switch is adapted to be closed first and to connect the motor to the line through a transformer or the equivalent whereby to reduce the voltage on the motor at the instant of starting. After the motor has been brought up to speed the starting switch is adapted to be opened and the running switch closed whereby to connect the motor directly to the line and exclude the transformer.

An object of this invention is the provision of means to govern the closing of the running switch automatically so that the running switch can not be closed until the motor has been brought up to about its normal running speed and the starting current has dropped to some predetermined low value. In carrying out this object of the invention, I may provide means governed by the starting current to lock the running switch against closing and said means may be so arranged that when the starting current has dropped to a predetermined value, as normal full load, it will operate to release the lock on the running switch, and thereby permit the running switch to close and the motor to be connected directly to the line.

A further object of the invention is generally to improve the construction and operation of motor starting apparatus and systems.

Fig. 1 is a diagrammatic representation of the motor starting apparatus and system embodying the invention.

Fig. 2 is a detailed elevation partly in section of a portion of the operating mechanism of a switch with which the invention is associated.

Fig. 3 is a sectional view taken along line 3—3 of Fig. 2.

The motor starting apparatus and system embodied in this invention may include a switch 10 which is adapted to connect the line 11 with an auto-transformer 12 or equivalent device whereby to energize the transformer. A starting switch 13 may serve to connect intermediate taps of the auto-transformer with circuit leads 14, which leads may extend to the motor, not shown.

The switch 10 and the starting switch 13 may be mechanically interconnected as by the rod 13^a whereby both switches may be opened or closed simultaneously and both switches may be herein termed the starting switch.

A running switch 15 is provided to connect the motor directly to the line 11 and exclude the auto-transformer 12 when the running switch 15 is closed. In starting the motor, the switches 10 and 13 are first closed and the motor is connected to the line through the auto-transformer and supplied with a reduced potential. When the motor has been brought up to speed the switches 10 and 13 are adapted to be opened and the switch 15 is adapted to be closed and the motor may thereby be connected directly to the line.

This invention may be associated with many types of motor starting apparatus, as automatically operated apparatus but, for purposes of simplicity, it is herewith described in connection with manually-operated apparatus.

A switch well adapted for this invention may be substantially as set forth in my co-pending application Serial No. 606,678, filed

December 13, 1922, and Figs. 2 and 3 illustrate certain details of the switch operating mechanism. The starting switch and the running switch may be substantially alike although this is not essential. Each switch may comprise the face plate 20, the lower end of which is formed to provide a coil compartment 21. Tripping coils 22 may be received in said compartment and a third coil 23 may also be received in said compartment and the function of said third coil 23 will hereinafter be more fully set forth. Each coil may be provided with a core or plunger 24 which, when the coil is sufficiently energized, is adapted to be moved upwardly and strike against a trip pin 25. Said trip pin is extended upwardly from within the coil and through a pedestal 26 and is formed with an enlarged and grooved head 27 at its upper end. A triangularly shaped tripping plate 28 is disposed above the coil compartment and may be formed with notches 29 therein into which the grooved heads 27 of said tripping pins 25 are adapted to be loosely received. The arrangement is or may be such that when any one of said tripping pins 25 is elevated it serves correspondingly to elevate the tripping plate, said tripping plate being rotated about the other two pins as fulcrums, or, if all of said pins are elevated, they all serve to move the tripping plates bodily upward for the purpose of tripping the switch.

The switch operating mechanism includes an operating handle 30 which may be pivoted at 31 to the front wall of the coil compartment. A latch 32 may be arranged to engage said handle when it is moved into a vertical position or in a position corresponding with the closed condition of the switch and thereby hold the switch closed. Said latch may be elevated manually to permit the handle to be moved outwardly away from the face plate or into a position corresponding to the open position of the switch. An arm 35 is or may be pivoted at 31 concentrically with said operating handle 30 and an operating link or rod 36 may be pivoted to said arm 35 and extend to the movable contact members of the switch. Means are or may be provided to connect said handle 30 releasably with said arm 35 whereby the switch may be opened and said arm may be moved to a switch-open position independently of a corresponding movement with the switch operating handle 30. Said means may include a latch 38, which latch may be pivoted to a bracket 39 of the operating handle 30. Said latch is adapted to engage a projection as the latch roller 40 of said arm 35 and the arrangement is or may be such that when said latch is in engagement with said roller, as indicated in Fig. 2, said arm 35 may be moved with said handle 30 between switch-open and switch-closed positions and when said latch 38 is moved into a disengaged position with said latch roller 40, said arm 35 may be free to move into switch-open position independently of the handle. Said latch 38 is adapted to be tripped by the tripping plate 28 and, for this purpose, may have a depending ear 42 which is adapted to be disposed above and in a position to be engaged and elevated by said tripping plate. It is apparent that an upward movement of the tripping plate, due to the energization of one of the coils 22, or the coil 23, will cause the disengagement of the latch from the roller 40 and thereby permit the switch to open independently of the corresponding movement of the operating handle.

Means are preferably provided to interconnect the mechanisms of the starting and running switches so that but one switch can be closed at a time and when the running switch is closed, the starting switch must be opened. Any suitable form of interlocking mechanism may be provided. As here shown, the mechanism may comprise the interlocking rod 50. Said rod may extend between the arms 35 of the starting and running switches and may be provided with elongated slots 51 and 52 in the ends thereof. The starting switch arm may be provided with a projection as the pin 53 which is adapted to be received within the slot 52. The running switch arm may be provided with a similar projection as the pin 54 which is adapted to be received within the slot 51. The arrangement is or may be such that if the starting switch is closed and the running switch is moved toward closed position, the movement thereof will cause the starting switch to be opened. For this purpose, the latch on the starting handle corresponding to the latch 32 on the running handle may be omitted so that the starting switch must be held manually in closed position while the motor is brought up to speed.

In accordance with this invention, I provide means to prevent the closing of the running switch until the motor has been brought up to speed or at least until the starting current has been reduced to a value corresponding about with the normal full load running value. Said means may include a current transformer 60 which transformer may be associated with the circuit including the starting switch 13 and arranged to be energized by the starting current. Said current transformer may be arranged to energize the tripping coil 23 associated with the running switch 15 in such a manner as to hold the tripping plate of said running switch in elevated position and thereby prevent the closing of the switch until the current has fallen to a predetermined low value. For this purpose, an excess current relay 62 may be arranged in

the circuit leads 63 and in series with the secondary of the current transformer 60 and said coil 23. Said excess current relay is or may be arranged to have relatively low resistance and also be so arranged that, when the current in the current transformer 60 is at some predetermined low value, its movable member 64 is in a position to bridge the stationary contact members 65 5 and thereby shunt the trip coil 23 and prevent current passing through said coil. When, however, the starting switch is operated and a heavy current passes through the motor said excess current relay is adapted to be energized by the current transformer to elevate its movable bridging-member 64 and break the connection between its stationary contact members whereby to cause the current to flow from said 10 current transformer through the tripping coil 23 and thereby raise the tripping plate of the running switch and prevent the running switch from being closed.

It will be noted that the connections of the excess current relay are such that when sufficient current flows through the coil 23, the bridging member 64 of said relay is maintained in elevated position and free from bridging contact with the stationary 25 contact members 65. When the motor has been brought up to speed and the starting current has dropped to the normal running current or some other predetermined reduced value, said excess current relay is arranged to be insufficiently energized whereby to permit the bridging member 64 thereof to drop and shunt the trip coil 23 thereby to lower the trip plate of the running switch. The running switch may then be 30 closed and connect the motor directly to the line and exclude the auto-transformer. For certain purposes, the excess current relay may be omitted and the tripping coil 23 connected directly to the current transformer.

45 When the apparatus is associated with manually controlled starting and running switches visual means are preferably provided to indicate to the operator the proper time to close the running switch. Said 50 means may include a target 70 of some distinctive color visibly displayed. As here shown, said target 70 is applied to the lower end of the plunger of the coil 23, see Fig. 2. When said target is in an elevated position, it serves as an indication that the motor has not yet attained its normal running speed and the running switch should not be closed. When, however, said target drops, it indicates to the operator that the running 55 switch may be closed.

The invention may be otherwise modified without departing from the spirit thereof.

I claim:

60 1. Motor starting apparatus including manually operable starting and running

switches and means rendered effective by an excessive motor current to prevent the closing of the running switch.

2. Motor starting apparatus including a starting switch free for movement in a closing direction and a running switch and means governed by the motor starting current to prevent the closing of the running switch. 70

3. Motor starting apparatus including a starting switch and a running switch and means associated with the starting switch arranged to hold the running switch against closing until the motor starting current is at a predetermined value. 75

80 4. Motor starting apparatus including independently operable starting and running switches, interlocking means arranged to hold either switch open when the other switch is closed, and means governed by the speed of the motor to prevent the closing of the running switch. 85

5. Motor starting apparatus including independently operable starting and running switches, interlocking means arranged to hold either switch open when the other switch is closed, and means governed by the motor starting current to disable the running switch and prevent the closing thereof. 90

95 6. Motor starting apparatus including a starting switch, a running switch, interlocking mechanism arranged to hold either switch open when the other switch is closed, and means governed by the motor starting current to disable the running switch and prevent the closing thereof until the starting current has dropped to a predetermined value. 100

105 7. Motor starting apparatus including independently operable starting and running switches, interlocking means arranged to hold either switch open when the other switch is closed, and means energized by the motor current arranged to disable the running switch to prevent the closing thereof until the starting current has dropped to a predetermined value. 110

115 8. Motor starting apparatus including a manually-operated starting switch, a manually-operated running switch and visual means governed by the motor starting current to indicate the proper time for opening the starting switch and closing the running switch. 120

125 9. Motor starting apparatus including a starting switch, a running switch, a coil arranged to be energized by current traversing the starting switch to disable the running switch, and a relay energized by the current traversing the starting switch arranged to govern the operation of said coil.

10. Motor starting apparatus including a starting switch, a running switch having locking means arranged to hold the switch in closed position, and means governed by 130

the motor starting current arranged to disable said locking means and prevent the closing of the running switch until the motor starting current has dropped to a predetermined low value.

11. Motor starting apparatus including a starting switch, a running switch having operating mechanism, an operating member and means releasingly connecting said operating member and mechanism, whereby to permit said operating member to close the switch, and means governed by the current traversing the starting switch to disable said connecting means and prevent the closing 10 of the running switch.

12. Motor starting apparatus including a starting switch, a running switch having operating mechanism, an operating member, a latch connecting said member and mechanism releasingly, a tripping device 20 arranged to be moved to actuate said latch and release the connection between said operating member and mechanism, and means governed by the current traversing the starting switch arranged to operate said tripping device and said latch and prevent the closing of the running switch. 25

In testimony whereof, I have signed my name to this specification.

CHESTER D. AINSWORTH.
